United States Patent Office

Des. 183,872
Patented Nov. 11, 1958

183,872

FLOOR POLISHER OR SIMILAR ARTICLE

Walter C. Anderson, Southport, and Robert J. Reading,
Stratford, Conn., assignors to General Electric Com-
pany, a corporation of New York

Application April 17, 1957, Serial No. 45,768

Term of patent 14 years

(Cl. D9—2)

Fig. 1 is a front elevation view of the housing portion of a floor polisher or similar article shown in Fig. 5.

Fig. 2 is a top plan view thereof.

Fig. 3 is a rear elevation view thereof.

Fig. 4 is a side elevation view thereof.

Fig. 5 is a perspective view of the floor polisher or similar article embodying our new design.

The dominant feature of our design resides in the housing portion of the floor polisher.

We claim:

The ornamental design for a floor polisher or similar article, substantially as shown and described.
